(57) **CLAIM**

We claim the ornamental design for a media device, as shown and described.

DESCRIPTION

FIG. 1 is a front elevation view of a media device showing our new design;

FIG. 2 is a rear elevation view of the media device;

FIG. 3 is a left side elevation view of the media device;

FIG. 4 is a top plan view of the media device;

FIG. 5 is a bottom plan view of the media device;

FIG. 6 is a front perspective view of the media device; and,

FIG. 7 is a perspective view of the media device as shown in FIG. 6, from which the broken line features have been omitted.

The broken line drawings of objects presented on the front-facing surface of the media device shown in FIGS. 1 and 6 indicate non-claimed possible displayed content that has been superimposed on a continuous claimed surface. The broken line drawings of features shown at the top and bottom of the media device shown in FIGS. 1–3 and 6 indicate environmental structure that has been superimposed on a continuous claimed surface. In all of the figures, the broken line features form no part of the claimed design.
